UNITED STATES PATENT OFFICE

135,805

DESIGN FOR A BRIDGE LAMP

Donald A. Wallace, Washington, D. C.

Application March 27, 1943, Serial No. 109,828

Term of patent 3½ years

To all whom it may concern:

Be it known that I, Donald A. Wallace, a citizen of the United States, residing at Washington, D. C., have invented a new, original, and ornamental Design for a Bridge Lamp, of which the following is a specification, reference being had to the accompanying drawing, forming part thereof.

Fig. 1 is a side elevational view of a bridge lamp, showing my new design, and

Fig. 2 is a detail sectional view thereof taken substantially on the plane of the line 2—2 of Fig. 1.

The dominant features of the design reside in the portions shown in full lines.

I claim:

The ornamental design for a bridge lamp, as shown and described.

DONALD A. WALLACE.
